DESIGN FOR A TOMBSTONE

Lena Maldera, Ozone Park, N. Y.

Application May 10, 1940, Serial No. 92,262

Term of patent 3½ years

To all whom it may concern:

Be it known that I, Lena Maldera, a subject of the King of Italy, and having been a resident of the United States since January 13, 1920, and at present a resident of 90-11 Albert Road, Ozone Park, Long Island, in the county of Queens and State of New York, have invented a new, original, and ornamental Design for Tombstones, of which the following is a specification, reference being had to the accompanying drawing, forming part thereof.

The figure is a perspective view of a tombstone showing my new design.

I claim:

The ornamental design for a tombstone, as shown.

LENA MALDERA.
